United States Patent Office.

ROBERT B. FORBES, OF BOSTON, MASSACHUSETTS.

Letters Patent No. 101,851, dated April 12, 1870.

IMPROVEMENT IN RIGGING FOR VESSELS.

The Schedule referred to in these Letters Patent and making part of the same.

I, ROBERT B. FORBES, of Boston, in the Commonwealth of Massachusetts, have invented certain Improvements in the Rigging of Fore-and-aft-rigged Vessels, of which the following is a specification.

The principal feature of my invention is the employing of traveling stays and stay sails between the masts of two or three-masted schooners in the place of the sails and rigging now in use, and in dispensing with gaffs.

The drawings represent this improvement when applied to a three-masted schooner, as follows, namely:

Figure 1 shows the schooner under all fore-and-aft canvas.

Figure 3, the same with the four upper sails furled, and the top-mast-stay sails partially lowered, which is equivalent to reefing them.

Figure 3, the same under close reefs, that is to say, the bonnets off the jib and the two lower stay sails, and the mizzen with two reefs in it.

Letters represent in each figure the same thing.

Letters *a a* represent the lower stay sails.

Letters *b b*, the bonnets on the same.

Letters *c c*, the top-mast-stay sails.

Letters *d d*, the gaff-top sails.

In the drawings the stays are designated by name.

Between the masts of schooners having either two or three masts I provide stays that travel up and down on the masts, between which they are passed by means of rings or other devices, as follows, that is to say:

The lower stays are moved on the masts up to and down from the points where the lower fixed stays are fastened to said masts. This allows them to be lowered and hoisted sufficiently to admit of removing or fixing the bonnets to the stay sails which they respectively carry.

The upper traveling stays have their forward ends, respectively, travel on the mast next forward up to and down from the point where the forward end of the upper fixed stays are fastened to said masts, while the other ends of said upper traveling stays travel on the top-masts of the masts next aft, up to and down from the points where the rear end of the upper fixed stays are made fast to their respective masts.

These traveling stays are hoisted and lowered by means of tricing-tackles or other well-known means.

Between each two masts I have two sails, a lower and an upper, besides the gaff-top sail, each carried by or traveling on one of the above-described traveling stays.

The two lower of these sails have booms and bonnets at their foot, and their heads are provided with bunks, rings, or bull's-eyes, or other usual means, and made to move back and forth on said stays by means

of halyards, and down-hauls, or equivalent means, as usual.

When it becomes necessary to reduce the sail by removing the bonnets, the stay is lowered sufficiently to allow this to be done, or when the sail is to be completely taken in or lowered, the halyards are let go, and the sail runs down on the stay with the help of down-hauls; then the tricing-tackles are slackened and the luff of the sail runs down to the point where it is to be furled.

The sails next above are called top-mast-stay sails. They travel up and down their respective stays, and are set and taken in in a manner similar to that above described, with the exception that they are not provided with bonnets.

Above these top-mast-stay sails, I have a sail which I call here a gaff-top sail, because it occupies the position of a gaff-top sail in ordinary schooners. They are set by means of hoops on the top-mast, or by hoisting from the deck with a yard attached, as usually done; but, inasmuch as in this rig there are no gaffs between the masts, the sails next below being carried on stays, the clew is hauled aft like a stay sail clew, to any convenient point, instead of being hauled out to a gaff.

The sails forward of the fore-and-aft of the mizzen-masts are the same as usual, as to size and the modes of setting and taking in.

In large fore-and-aft vessels, rigged in my way, the sails between the masts are smaller in size and more easily reduced or furled than those of vessels of the same tonnage rigged in the old style.

As the lower sails, called storm sails, very seldom require reefing or reducing by removing their bonnets, they should be of the heaviest canvas, while the upper sails should be much lighter.

In the present rig, and especially in large schooners, the sails are heavy to handle, and in stormy weather and when once reefed, in a gale of wind, the reefs cannot safely be let out, in case of a temporary lull, to steady the vessel; whereas, in the new rig, suppose the vessel, as in fig. 3, to be under short canvas, if a lull should occur, the top-mast-stay sails can be more easily set, and if a sudden change or increase of wind makes it necessary, more easily taken in again than in vessels of the present rig.

I claim that the rig above described has many advantages over the rig at present in use, and among them the following, viz:

By dispensing with gaffs, much wear and tear are avoided, many heavy blocks, ropes, and winches are rendered unnecessary, the sails will be more out of the way when furled in port, and the booms may be used as derricks for hoisting cargo in and out.

The new rig is cheaper in original cost, and in gen-

eral wear and tear; it is safer in stormy weather, and will propel better in whole-sail weather, except when going dead before the wind.

The fixed stays support their respective masts much better than the usual cross-stay.

The masts need not be so long nor so large in my rig. This is an important advantage, as masts fitted for large schooners are very expensive in this country, and it is almost impossible to obtain them abroad.

Vessels rigged in this way will be much more easily worked, as there will be only rare occasions to go aloft more than fifteen or twenty feet, if the so-called gaff-top sails are fitted to set from the deck.

In adapting this rig to two-masted schooners it is best to spread the masts a little, so as to reduce the main-boom and sail and the main-jib, whereby more sail will be carried in the body of the body of the vessel between the masts.

As by this rig it is impossible to wing out as amply as in the old rig, I recommend to have a large square sail, with the yard to which it is hoisted so rigged as to travel on a strong rod which can be stowed up and down the forward mast, as shown in fig. 2, letter f.

I claim as my invention—

1. The combination of stay sails running on traveling stays, with said stays and with gaff-top sails worked without gaffs, all between the masts of schooners.

2. The combination of traveling stays with stay sails running thereon between the masts of schooners in the place of the common gaff sails, all substantially as and for the purposes hereinbefore set forth.

R. B. FORBES.
